UNITED STATES PATENT OFFICE.

THOMAS COLLIER, OF COLNE, ENGLAND.

FURNACE OF STEAM BOILERS.

Application filed September 23, 1922. Serial No. 590,126.

To all whom it may concern:

Be it known that I, THOMAS COLLIER, residing at 24 Fern Street, Colne, in the county of Lancaster, England, have invented 55
certain new and useful Improvements in or Relating to the Furnaces of Steam Boilers, of which the following is a specification.

This invention relates to a Bunsen blower for use in connection with furnaces, steam generators, and the like and comprises a fan like body divided into a number of compartments open at each end and adapted to be secured underneath the dead plate of the fire grate. At the front end is a steam pipe 10
15 with nozzles or jets projecting into each compartment and at the rear end are two superposed deflecting plates arranged at different angles, the upper plate advantageously being capable of having its position adjusted. 20
25 The steam leaving each jet induces a current of air through each compartment which is distributed to the best advantage underneath the grate, producing better combustion of fuel, reducing smoke and effecting considerable economy in the consumption of coal.

In the accompanying drawings:—

Fig. 1 is a perspective view of a Bunsen blower constructed in accordance with this invention.

Fig. 2 is a side elevation partly in section.

Figs. 3, 4 and 5 are details of a modified construction in which the upper deflecting plate is made adjustable, and

Fig. 6 is a section showing the blower in position in a steam generator of the Lancashire type.

A indicates the fan like body, B the steam pipe, and C and D the two deflecting plates.

The body A is constructed from an upper portion and a lower portion secured together by bolts α and it is separated into a number of compartments by partitions α^1 which diverge as shown in Fig. 1. At the front end of the body are two lugs α^2 which support the steam pipe B and projecting from the latter are a number of nozzles β one of which enters each compartment. The lower portion of the body is formed with grooves α^3 which rest on supporting bars α^4 which extend across the boiler flue below the fire grate (Fig. 6). The deflecting plates C and D are respectively attached to and formed in a piece with the lower portion of the body

at the rear end and the plate C is arranged at a steeper angle than the plate D so that 55 the air, or air and steam will issue through the upper aperture at a steeper angle than the air, or air and steam which issue through the lower aperture. In the modification shown in Figs. 3 and 5 the plate C is slidably mounted above the plate D and can be secured in any adjusted position by a set screw c . This construction enables air and steam to be directed more to the front, or more to the rear of the grate to suit any particular requirement. 60
65

What I claim as my invention and desire to secure by Letters Patent of the United States is:—

1. A Bunsen blower, adapted to be secured under the dead plate of a furnace, comprising a fan-shaped body open at each end and divided by partitions into a series of compartments which are wider at their outlets than at their inlets, the bottom of the outlet end portion of the body being inclined upwardly beyond the rear ends of the compartments, a deflecting plate secured over the inclined end portion and arranged at a steeper angle than it, and a steam pipe 70
75 arranged crosswise of the open inlet end of the body and having a series of nozzles 80 which project into the air inlet openings of the compartments.

2. A Bunsen blower for use in connection with furnaces, steam generators and the like comprising a fan like body open at each end and adapted to be secured underneath the dead plate of the fire grate, a number of partitions situated in said body and separating same into a number of compartments which increase in width towards the rear end of the body, the bottom of which inclines upwardly beyond the ends of the compartments, a deflecting plate extending across the ends of the compartments above the inclined bottom portion and arranged to be moved towards and away from said ends, means for securing the deflecting plate in its adjusted position, and a steam pipe adapted to be supported across the front end of the compartments and having a number of nozzles one of which projects into each compartment. 90

100

In testimony whereof I affix my signature.

THOMAS COLLIER.
